XEROGRAPHIC COPIER

Donald A. Robertson, Fairport, and Craig A. Smith, Pittsford, N.Y., assignors to Xerox Corporation, Stamford, Conn.

Filed Aug. 8, 1974, Ser. No. 495,606

Term of patent 14 years

Int. Cl. D16—03

U.S. Cl. D61—1 Q

FIG. 1

FIG. 2

FIG. 5

FIG. 4

FIG. 6

FIG. 1 is a front perspective view of a xerographic copier showing our new design;

FIG. 2 is a front elevational view thereof;

FIG. 3 is a rear elevational view thereof;

FIG. 4 is a right side elevational view thereof;

FIG. 5 is a left side elevational view thereof; and

FIG. 6 is a top plan view thereof.

The characteristic features of our design reside in the platen cover and tray units.

We claim:

The ornamental design for a xerographic copier, as shown and described.
